UNITED STATES PATENT OFFICE.

NORRIS ELMORE CLARK, OF PLAINVILLE, CONNECTICUT, ASSIGNOR TO ROBERT S. ALLYN, TRUSTEE, OF NEW YORK, N. Y.

EXPANDED-METAL MANUFACTURE.

1,321,089.

Specification of Letters Patent. Patented Nov. 11, 1919.

Application filed December 7, 1916. Serial No. 135,518.

To all whom it may concern:

Be it known that I, NORRIS ELMORE CLARK, a citizen of the United States of America, residing at Plainville, Connecticut, have invented a new and useful Expanded-Metal Manufacture, of which the following is a specification.

This application sets forth improvements in processes of making expanded metal as well as machines for carrying out such processes and also the product thereof.

The main object is to form a rigid and desirable expanded fabric economically. Specifically, I have sought to devise a process in which the metal may be slit longitudinally, for instance, by rotary cutters and expanded in the same machine by a separate step in such a way that the distinctive lines of bonds will extend diagonally of the sheet in zig-zag arrangement so that the sheet has lateral as well as longitudinal stiffness. The finished product will be found made up of sections, the strands of adjacent sections being inclined in opposite directions in what has become known as a reverse-lay. The methods and mechanisms herein described are such as are known as of the reverse-lay-section type, inasmuch as they produce in the material acted upon a plurality of expanded metal sections, wherein the angularity of strands of one-half of each section is reversely laid with respect to the strands of the adjacent half section or the strands of adjacent sections are in reverse lay. The lengthwise opening of the meshes of one-half section is preferably at an angle to the lengthwise opening of the meshes of the adjacent half section.

This combination of reverse-lay angularity of strands and oppositely disposed mesh openings produces greater uniform stiffness throughout the entire finished sheet and likewise renders the product more universal in its application in that it may be erected and plastered up on either side or with any edge uppermost.

To manufacture a product of the qualities above described, I have found it practicable and economical to cut the metal blank into slit sections, longitudinally corrugate the slit sections to open the meshwork and then spread the sheet or flatten the corrugations. In general such a method produces a reverse-lay as for instance, in my Patents #930,350; #979,130; #1,052,

888; #1,104,475; #1,104,476; #1,104,477; #1,128,659; #1,134,513; #1,146,552 and #1,146,553.

However, in my present invention instead of slitting the metal blank at an angle to the outer edges thereof, which is somewhat difficult with rotary mechanisms, I have devised means for making a product in which the cuts are all parallel to the outer edges especially suitable for rotary cutting and so arranged with respect to each other that many of the desired qualities in the finished product as previously outlined are still retained.

In the specific form illustrated and described herein, the stock is first slit longitudinally by means of rotary cutters which are arranged so that the bonds between the cuts lie along lines inclined in the direction of feed and so that the direction of inclination of these rows of bonds is reversed at regular intervals, each bond being arranged near the ends of the laterally adjacent slits except along the center lines of the slit sections where the lines of bonds change direction. The slit stock is preferably fed downward on an incline through the slitting rolls to transverse corrugating disks or rolls which engage edges of the sheet and interior longitudinal portions of the sheet along the lines of the edges of the slit sections. The centers of the slit sections are guided in their original inclined plane along the line of engagement of the inclined rows of bonds. The corrugating disks serve to bend the marginal strips of each slit section and apply a stretching force along the inclined lines of the bonds so as to bend all of the strands connected to that particular line of bonds and thus open the mesh. This produces an expanded mesh work product zig-zag or corrugated in cross section which may be subsequently spread or brought into a common plane. It will also be apparent that marginal and interior strips of the stock may be made materially broader than the strands of the mesh work so as to provide relatively deep ribs projecting from the plane of the mesh work.

Figure 1 is a fragmentary plan view of a fabric of my invention of substantially uniform thickness, made according to the method herein set forth.

Fig. 2 is an end view of the fabric, more or less diagrammatic and also showing forming dies.

Fig. 3 shows the arrangement of slitting at one edge of a sheet and indicating the zig-zag arrangement of bonds.

Fig. 4, is a vertical section and fragmentary elevation of the mechanism for opening the meshwork and showing the product in that stage of the process.

Fig. 5, is a diagrammatic side view and longitudinal section illustrating the mechanism for carrying out the process and suggesting the product at its various stages.

Fig. 6, is a similar plan view.

Fig. 7, is an enlarged detail view showing in side elevation the mechanism for opening the slitted stock.

Fig. 8, is a detail perspective view of a deep ribbed type of product made according to this process.

Fig. 9, is a similar view of a ribbed type of product with closed ribs.

Fig. 10 is a diagrammatic side view illustrating supplemental corrugation of some of the longitudinal strips.

Fig. 11, is a detail perspective view of a deep ribbed product with a plurality of relatively small transverse corrugations in the deep ribs and one rib having a reverse flange.

Fig. 12, is a detail sectional view showing the doubling of the strips.

Figs. 13 and 14 are detail views of a form of abutment with stepped edges.

The broad idea of the method will perhaps be more readily understood by first considering one form of product, for instance, the lath of substantially uniform thickness shown in Figs. 1 and 2. This has a plurality of strands such as 10, 11 and 12 connected together at intervals by bonds such as 13 and 14. The marginal strip 15 is preferably wider than the strands which form the main part of the fabric. The marginal strip 15 is connected with the adjacent strand 10 by bonds such as 16, which are preferably somewhat longer than the bonds 13—14, etc. The strip 17 is connected with the adjacent strand 18 by bonds such as 19. All of the strips and strands at the left of Fig. 1, it will be seen, are inclined edge-wise downward and toward the left, whereas the strand and strips at the right are inclined downward and toward the right. The strip 20 is connected to the adjacent strand 21 by a plurality of bonds similar to 19, and the strips 17 and 20 are connected together along the center of the section by bonds such as 22, which are preferably longer than the bonds 19 or 13. It will be seen from an inspection of Fig. 1 that the bonds at the left are arranged along diagonal lines such as 23 extending upward and to the left, whereas the bonds at the right are arranged along diagonal lines such as 24 extending upward to the right. This arrangement of bonds and strands affords more stiffness than where the bonds are ar-

ranged longitudinally or transversely of the fabric.

Fig. 3 illustrates the arrangement of slitting to produce the strands and strips just mentioned. It will be noted here that the slits or cuts 26 and 27 are so arranged that each bond such as 13 comes opposite a point near the end of one adjacent slit 26 and near the opposite end of the other adjacent slit 27. It will be seen that the slitting is such that the bonds in the left hand part of the left hand section are arranged along diagonal lines such as 23' inclined upward and to the left at acute angles to the length of the sheet, and that the slits in the right hand part of the left section are arranged so that the bonds are inclined diagonally along lines such as 24' inclined upward and to the right. 28 indicates one of the slits along the center of the section just described. 29 indicates the strand at the right of the slitted section just described. These slitted sections are repeated across the sheet and I have illustrated by dotted lines 30, 31, 32 and 33 the direction of the rows of bonds in successive sections. In the form shown in Fig. 3, a row of slits such as 34 extends between the left hand slitted section and the next adjacent section.

In Fig. 5, 35 and 36 are the rolls or cutters for slitting the stock as above described. 37 indicates an introductory feed table. 38, 39 and 40 indicate pairs of feed rolls. 41, 42 and 43 indicate guides for directing the stock through the feed rolls and the slitting rolls. These are preferably arranged on an incline so that the finished stock may come out on a horizontal plane.

The rolls 40 may be so adjusted as to smooth out the slitted stock if desired, and for serving to feed it to the opening mechanism through the guides 44 and 45. Across the machine are arranged a series of abutments 46 having their lower rear faces inclined (see Fig. 7) relative to the horizontal at an angle equal to the angle which the rows of bonds (see Fig. 1) in the finished product make to the edge of the fabric. These abutment faces are tapered to correspond with the angle of convergence of the rows of bonds of the slitted stock represented by the dotted lines 23' and 24' (see Fig. 3). At the side of each abutment is arranged an expanding disk 47 having teeth 48 meshing with the teeth on the smaller disk 49 above. The teeth 48 are shaped so as to engage and bend the longitudinal strips such as 15 and 29 of the slitted stock as the slitted stock passes downward beneath the abutments 46. These strips are bent upward as they move forward as shown in Fig. 7, the teeth corresponding to the meshes of the finished product. The disks 47 are mounted on the shaft 50 and the disks 49 on shaft 51. The lower shaft is

preferably driven and the upper shaft may also be driven. The lower end of each abutment 46 is shaped at 53 to permit the central strips 17 and 20 to take a bend corresponding to the bend of the strips 15 and 29. In operation the force applied to bend the strips 15 and 29 is transmitted to the slitted stock along the lines such as 23' and 24' of the bonds so as to bend all of the 10 strands connected therewith and open the meshwork.

The abutments 46 may all be carried by a stationary cross bar 54 being secured thereto by means of screws 55 passing through elongated slots 56 so as to permit the abutments to be adjusted on an incline corresponding to the angle of inclination of the slitted stock. This adjustment will vary the degree and character of expansion to 20 some extent. A set screw 57 may be provided for forcing each individual abutment down the incline. Each abutment is preferably provided with a tail-piece 58 which extends up between the upper expanding 25 disks 49. Each abutment also preferably has a shoulder 59 at each side which serves to prevent the marginal strands of each slitted section from drawing in toward each other or out of the grip of the expanding 30 disk. The toe 53 may be adjusted up and down the incline or vertically independent of the body of the abutment.

After the slitted stock has been opened into oppositely inclined meshwork as indicated in Fig. 4, it may be laterally spread into a common plane by suitable means for instance, rolls and guides such as illustrated in my Patent #1,146,552, or #1,146,553 or in my Patent #1,224,877. Rolls for spreading the meshwork are indicated diagrammatically in Figs. 5 and 6 by the reference numerals 60, 61 and 62.

The bending of the bonds 22 into V-shape so as to permit the strands to lie naturally on each side thereof may be facilitated by suitable dies such as 63 and 64 indicated in Fig. 2. Preferably this action is affected or at least partially affected before the fabric is flattened out and preferably early in 50 the spreading action.

Some of the longitudinal strips may be made very much broader than the strands as indicated in Fig. 8 so as to form very substantial ribs 65 projecting from the 55 plane of the expanded meshwork.

In case the longitudinal strips are not slitted down the centers, the metal may be drawn over so as to permit of folding into ribs as indicated in Fig. 9.

60 In some cases for instance when the central strips of each slitted section are much broader or stiffer than the strands it may be desirable to apply force by means of suitable dies to corrugate them at the lower 65 ends of the inclined abutments for instance,

by locating additional crimping disks at these points such disks being similar to 47 and 49 but of a size permitting this arrangement. Such supplemental mechanism would assist in the opening action.

The broad marginal and interior strips may be subsequently modified after the meshwork is formed as for instance by additional transverse corrugations 67 and 68 as shown in Fig. 10, thus substituting a 75 plurality of shallow transverse corrugations for the single corrugation or loop of each meshwork.

Such transversely corrugated strips may subsequently be more easily folded in to 80 deep ribs if desired as shown at 69 in Fig. 11.

In a fabric having a reverse lay of strands it is desirable in some cases to have alternate ribs provided with reverse flanges so that the strands may take a natural bend as 85 shown at 70 in Fig. 11. The edges of the ribs are thus inclined at substantially the same angle as the inclination of the meshwork.

The large corrugations or loops may be 90 folded or doubled over on themselves as shown in Fig. 12 and rolled tightly together so as to form a relatively flat strip. Such strips may be subsequently longitudinally corrugated by means of suitable rolls so as to form deep ribs. Such ribs will be especially rigid as they are in places three times as thick as the rest of the sheet. This also provides roughened surfaces which tend to increase the bonding effect in the concrete. 100 The edges of the abutments 46 may be provided with steps 46' of the width of the strands so that each strand may be drawn over a corner.

In making the product the material of the 105 strands may be somewhat elongated or stretched and in fact the material may be made having the general appearance of that shown in Figs. 1 and 2 in which the material of the strands is very substantially elongated. The strands may even be elongated sufficiently to permit the use of straight ribs in place of the transversely corrugated ribs. To make such a product the stock would be 110 slitted in the same general arrangement so far as the zig-zag lay-out of rows of bonds is concerned and as a result the finished product would have advantages similar to those of the product previously described 115 since it would have the diagonal arrangement of rows of bonds and the reverse lay of the meshwork.

The product is claimed in my application #290,040 filed April 14th, 1919.

What I claim is:—

1. In an expanded metal machine, means for slitting a sheet longitudinally across its entire width, means for transversely corrugating the edges and intermediate slitted strips of the slitted stock and means for en- 130

- gaging the slitted stock midway between the corrugating means and in advance thereof to open the slitted stock into oppositely inclined meshwork sections.
5. 2. In an expanded metal machine, means for slitting a sheet longitudinally across its entire width, means for transversely corrugating the edges and intermediate slitted strips of the slitted stock, means for en- 10 gaging the slitted stock midway between the corrugating means and in advance thereof to open the slitted stock into oppositely inclined meshwork sections and means for spreading said sections into a common plane.
15. 3. In an expanded metal machine, a series of transversely toothed corrugating rolls on a common axis, a series of materially larger toothed rolls coacting therewith, means for directing slitted stock at one angle to said 20 rolls and guiding the stock midway between laterally adjacent rolls to points beyond the coacting faces thereof to open the slitted stock and means for guiding the meshwork away at an angle to the unopened slitted 25 stock.
4. In an expanded metal machine, a series of transversely toothed corrugating rolls on a common axis, a series of toothed rolls co- 30 acting therewith, means for directing slitted stock at one angle to said rolls and guiding stock midway between laterally adjacent rolls to points beyond the coacting faces thereof to open the slitted stock, means for guiding the meshwork away at an angle to 35 the unopened slitted stock and spreading the meshwork into a common plane.
5. In an expanded metal machine, means for slitting the entire width of a sheet longitudinally, a series of transversely toothed 40 corrugating rolls on a common axis, a series of toothed rolls coacting therewith, means for directing slitted stock at one angle to said rolls and guiding the stock midway between laterally adjacent rolls to points be- 45 yond the coacting faces thereof to open the slitted stock and means for guiding the meshwork away at an angle to the unopened slitted stock.
6. In an expanded metal machine spaced 50 pairs of transverse corrugating rolls, means for directing slitted stock at an angle to said rolls between and beyond the same to open the meshwork, and means for guiding the open meshwork away from said rolls at an 55 angle to said directing means.
7. In an expanded metal machine, means for slitting the margins and intermediate strips of a sheet to form strands connected in staggered arrangement, means for slitting 60 the intervening portions of the sheet to form narrower strands connected in staggered arrangement and means for transversely corrugating the broader marginal and intermediate strands and opening the slitted stock into oppositely inclined sections.
8. In an expanded metal machine, a series of pairs of feeding rolls arranged on parallel axes, the rolls of each pair being spaced apart from the rolls of each adjacent pair, a guide between each of the adjacent pairs 70 of rolls, said guides being widest at the incoming end and tapering forwardly toward the center and inclined at a sharp angle to the plane containing the axes of said rolls and means for guiding the trough-shaped 75 meshwork away from said rolls and guides in a direction the general plane of which is inclined at a sharp angle relative to the surface of the guides between said rolls.
9. The method of forming expanded 80 metal which comprises, slitting the stock longitudinally in sections, transversely corrugating spaced longitudinal strips at the edges of the sections and directing and supporting the intermediate portion of the 85 slitted stock along lines inclined forwardly from the points of corrugation toward the centers of the sections and opening the mesh.
10. The method of making expanded 90 metal consisting in first slitting the sheet with relatively short longitudinal cuts, the 95 location of bonds between cuts of longitudinal series being off-set from the centers of the adjacent cuts and lines of bonds being in zig-zag arrangement transversely of the sheet, then opening the mesh by forming as many longitudinal corrugations as there are zig-zags of bonds and then flattening out the corrugations without closing the mesh.
11. The method of making expanded 100 metal consisting in first slitting the sheet into sections of longitudinal strands of uniform width and connecting bonds, sections being connected with each other by bonds and pairs of wider strands, then longitudinally corrugating the sheet at alternate 105 series of pairs of wider strands to form meshwork and foreshortening the sheet, and then flattening the corrugated sheet.
12. A machine for forming metal lath 110 comprising, a horizontal table, rolls for feeding the stock, downwardly inclined guides, rotary cutters for slitting the stock parallel to the edges of the stock as it passes down said guides, a series of pairs of spaced 115 toothed corrugating rolls, parts of said inclined guides being tapered and extending beyond the line along which said corrugating rolls engage the stock, and means for feeding away the meshwork.
13. In an expanded metal machine, a plurality of tapered guides, side by side in one plane, each guide being widest at the entrance end, means for bending the successive strands of previously slitted stock over 125 the edges of said guides to form troughed meshwork with oppositely inclined sections and means for guiding away the meshwork in a direction whose general plane is sharply inclined to the plane of the tapered guides.

14. In an expanding machine, guides for the slotted stock terminating in portions which taper forwardly, a series of large toothed corrugating rolls arranged to carry 5 certain strands of the slotted stock out of the plane of the guides and other toothed corrugating rolls coöperating with the first mentioned corrugating rolls but materially smaller in diameter to permit certain of the strands to be bent substantially as set forth.

15. In an expanding machine, guides for the slotted stock, the forward ends of said guides being tapered, means for adjusting the tapered ends, a series of large toothed 15 corrugating rolls for bending certain of the strands out of the plane of said guides and other smaller toothed corrugating rolls co-acting therewith for the purpose specified.

16. The method of forming an expanded 20 metal fabric which comprises slitting sec-

tions of a sheet parallel to the edges and in staggered arrangement, the bonds between the slits in each longitudinal line of slits being located adjacent the ends of the slits in the adjacent line of slits and the lines of bonds extending in zig-zag arrangement transversely of the sheet and bending the strands to form oppositely inclined mesh-work sections having rows of bonds and strands extending diagonally of the sections. 25

17. An expanded metal blank comprising a plurality of groups of strands each consisting of parallel longitudinal strands, adjacent strands being connected together by bonds located near the ends of the adjacent 30 slits, the slits and bonds being so arranged that there are rows of bonds connected by parts of strands extending diagonally in opposite directions in adjacent groups. 35

NORRIS ELMORE CLARK.
